UNITED STATES PATENT OFFICE.

MARY FRANCES MUNZ, OF MILWAUKEE, WISCONSIN.

WASHING APPARATUS.

1,390,636.

Specification of Letters Patent. Patented Sept. 13, 1921.

Application filed April 9, 1918. Serial No. 227,548.

To all whom it may concern:

Be it known that I, MARY FRANCES MUNZ, a citizen of the United States, and resident of Milwaukee, in the county of Milwaukee and State of Wisconsin, have invented new and useful Improvements in Washing Apparatus, of which the following is a description, reference being had to the accompanying drawings, which are a part of this specification.

This invention relates to improvements in washing apparatus more particularly adapted for household use.

It is the present custom in household laundries to provide separate fixed or movable tubs and an independent heating means for the laundry work. This causes considerable rehandling of the apparel being laundered and also frequent filling and emptying of the tubs with hot water and consequently a considerable amount of unnecessary labor.

It is one of the objects of the present invention to overcome the before mentioned objectionable features and provide a washing apparatus in the form of a unitary structure with which the entire washing may be accomplished with the minimum amount of work.

A further object of the invention is to provide as a unitary structure a washing apparatus with which the water may be heated, the apparel washed, rinsed and blued and put through the wringer without being removed from the apparatus.

A further object of the invention is to provide a washing apparatus consisting of a plurality of receptacles or tubs joined together and having a means for heating the water in one of the receptacles and also having a wringer holding frame which may be swung and maintained in a position of use adjacent any of the receptacles.

A further object of the invention is to provide a washing apparatus in which the receptacle in which the water is heated may be used in part and as a washing machine.

A further object of the invention is to provide a washing apparatus in which the various receptacles have hot and cold water supply pipes and also waste water pipes connected thereto.

A further object of the invention is to provide a washing apparatus which may be easily converted into a power driven machine if desired.

A further object of the invention is to provide a washing apparatus which is of simple construction is strong and durable and is well adapted for the purpose desired.

With the above and other objects in view the invention consists of the improved washing apparatus and its parts and combinations as set forth in the claim and all equivalents thereof.

In the accompanying drawings in which the same reference characters indicate the same parts in all of the views:

Figure 1 is a top view of the improved washing apparatus;

Fig. 2 is a vertical sectional view thereof taken on line 2—2 of Fig. 1;

Fig. 3 is a vertical sectional view taken on line 3—3 of Fig. 1;

Fig. 4 is a detail side view of the wringer supporting frame;

Fig. 5 is a sectional detail view of the wringer frame taken on line 5—5 of Fig. 6; and

Fig. 6 is a top detail view of the said wringer frame.

Referring to the drawings the numeral 8 indicates a semicircular receptacle which extends part way around and forms part of a central main receptacle or wash tub 9. Both receptacles are preferably formed of metal and the semicircular receptacle is divided preferably by two radially extending partitions 10 to form three compartments or auxiliary tubs 11. Legs 12 support the receptacles the desired distance above the floor. The bottom portion 13 of the wash tub 9 is elevated above the plane of the bottom portion of the semicircular receptacle to provide ample space to conveniently mount a gas burner 14 thereunder. Said gas burner is supported upon transverse rods 15 mounted upon portions of the auxiliary tubs 11 and is connected to a source of gas supply 16. Another gas burner 14' may also be mounted beneath one of the other tubs 11 to keep the water boiling hot during the entire washing process. While the burner shown is of the gas type it is to be understood that other forms of heating means may be used if desired.

The wash and auxiliary tubs are each provided with hot and cold water supply faucets 17 for supplying water thereto and also with discharge waste pipe connections 18, said waste pipe connections 18 being provided

with suitable valves or stoppers 19 for conveniently controlling the discharge of the water from the receptacles.

The upper portion of the wash tub extends 5 a short distance above the tops of the auxiliary tubs and is provided with a top 20 having a hinged cover 21 which adapts the tub to be used as a wash machine, a pounder 22 being shown as journaled in and extending 10 through the hinged cover for that purpose. Said pounder may be power driven or operated by hand as desired.

A semicircular wringer supporting member 23 of angular form in cross section is 15 mounted on the upper portions of the wash and auxiliary tubs and comprises a lower track portion 24 and an upper flange portion 25. A wringer frame 26 is slidably mounted on and has a rounded dovetail connection 27 with the track and an adjustable clamping connection 28 with the upper flange 25 so that said wringer frame may 20 be adjusted and clamped in any position around the supporting member. The said 25 wringer supporting member 23 is formed of two parts, and the upper part 29, on which the wringer 30 is mounted, is hinged at one end to the lower part by a hinge 31 to permit said upper part to be swung to a radial 30 position as indicated by dotted lines in Fig. 1. In the last mentioned position the upper swingable arm 29 is maintained in adjusted radial position by means of the clamping member 32 which extends over the edge of 35 the partition wall 10 engaged and is clamped thereto by the thumb bolt forming part of said clamping member. A clamping arm 33 pivotally mounted on one end of the lower

part of the supporting member 23 may be swung to a position to engage the free end 40 of the swingable arm 29 and is provided with a thumb screw 34 for clamping the swingable arm thereto.

From the foregoing description it will be seen that by means of the semicircular arrangement of the auxiliary tubs around the wash tub and the semicircular track and the wringer frame thereon the apparel being washed may be easily and conveniently handled from one tub to the other and when 50 desired may be easily passed between the rollers of the wringer. The location of the burners beneath the wash tubs provides for conveniently boiling the water used in washing. Furthermore the unitary structure of 55 the tubs and the supply and discharge pipe connections eliminate lifting and carrying pails of water to fill or empty the tubs. The construction and arrangement of the parts also provide for the driving of the rotary 60 parts by power means if so desired.

What I claim as my invention is:

A washing apparatus comprising a main tub, a semi-circular receptacle within the inner arc of which said main tub is secured, 65 said main tub having its bottom and top disposed on a plane above that of the bottom and top of said semi-circular receptacle, partitions in said receptacle to form a plurality of auxiliary tubs, all of said tubs 70 forming a unitary structure, and water supply and discharge means connected with the tubs.

In testimony whereof, I affix my signature.

MARY FRANCES MUNZ.
